ABRADING APPARATUS

John A. Keenan, New York, N. Y., assignor to
American Optical Company, Southbridge,
Mass., a voluntary association of Massachu-
sets

Application August 29, 1935, Serial No. 38,417

3 Claims. (Cl. 51—131)

This invention relates to an abrading apparatus and has particular reference to an improved attachment for use in abrading curved surfaces on lenses or articles of a similar nature.

5 The principal object of the invention is to provide improved means for prolonging the life and durability of an abrading machine and for obviating obnoxious noises during its use.

Another object is to provide an attachment 10 having means on the tool or work holding support which is subjected to the greatest amount of wear which may be removed and replaced with a minimum of expense.

Another object is to provide holding fingers 15 on the tool or work holding support having means for reducing the wear whereby the machine may be operated longer with a high degree of accuracy before replacement of the wearing parts of the fingers is necessary.

20 Other objects and advantages will become apparent from the following description taken in connection with the accompanying drawing and it will be apparent that many changes may be made in the details of construction and arrangement of parts without departing from the spirit of the invention as expressed in the accompanying claims. I, therefore, do not wish to be limited to the exact details of construction and arrangement shown and described as the preferred 25 form only has been shown by way of illustration.

Referring to the drawing:

Fig. I is a plan view of a tool or work holding support embodying the present invention;

35 Fig. II is a plan view of a modified form of the invention shown in Fig. I;

Fig. III is a cross section of a holding finger along the line III—III of Fig. I;

Fig. IV is a cross section along the line IV—IV 40 of Fig. II; and

Fig. V is a diagrammatic elevational view of an abrading apparatus in which the invention is adapted to be used.

45 Abrading machines employed in the production of lenses having curved or different powers formed on a face thereof, such as toric or cylindrical lenses, are provided with an attachment for keeping the tool and work in proper abrading relation with each other so that the 50 finished compound curve formed on the surface of the lens will be of the shape and power desired. The most accurately operating arrangement for abrading such lenses has been found in the past to be one formed with a pair of spaced 55 parallel upright supports pivoted diametrical-

ly opposite each other on the tool holder and provided with a work holder formed with a pair of horizontally disposed arms engaged between the diametrically opposed supports to hold the work against rotation in proper abrading relation with the tool. Although this type of attachment was very efficient in the production of high grade lenses, it had a very serious drawback in that it soon became worn and impracticable for use. 5

Another serious defect in this type of attachment was a tendency to produce a very displeasing and annoying noise during its use.

Since these upright supports and arms are 10 constantly operated in sliding contact under fairly high pressure they soon became worn so badly that the accuracy of the apparatus became impaired. Various means have been suggested for reducing the wear on these parts. In some instances the arms and/or upright members have 15 been provided with sleeves rotatably mounted so as to reduce the sliding contact wear on these parts. These sleeves must necessarily be round and, therefore, they engage on substantially a point contact which increases the pressure and 20 the wear on these parts is not reduced as much as might be expected. These sleeves do, however, reduce the wear appreciably but still the replacement cost is rather high because of the 25 sleeves being made of metal which is fairly expensive. 30

Accordingly, the main purpose of this invention is to reduce the wear whereby a greater accuracy is maintained, reduce the replacement cost and noise incident to the operation of these 35 machines.

Broadly speaking, the invention contemplates means for providing bearing inserts in either side of the guiding fingers of the tool or work holding support which can be very quickly and easily replaced and which may be so arranged that a maximum of wear may be obtained with the replaceable bearing inserts. 40

Particularly referring to the drawing, an embodiment of the invention comprises a work holder 1 of the usual prior art type having diametrically opposed arms 2 which are adapted to be engaged between two spaced upright guiding members 3, only one of which is shown, pivotally connected to the opposite sides of a tool support 4 45 of the usual prior art abrading attachment. Any conventional means, shown in the form of a crank pin 6 actuated by driving means 7, may be provided to move the tool relative to the work during 50 the abrading operation. It is to be understood 55

that during actuation of the work holder 1 carrying the work, such as the lens blank A, over the tool 8 the arms 2 will be caused to rock the spaced upright members 3 back and forth as well as 5 oscillate in the direction of the axes of the arms 2. The sliding of the arms 2 against upright arms 3 causes great wear on these parts since they are operating under high pressure.

According to my invention suitable replaceable 10 bearing inserts 10 are fixedly held in recesses 11 formed in the opposite sides of the arms 2. Since the work and work holder including the arms 2 must be frequently washed during the abrading operations, the inserts 10 must be capable of 15 withstanding frequent immersions in water and still retain their wearing quality and still remain frictionally engaged in the recesses of the arms 2. For this reason, the inserts 10 are preferably made of specially treated leather soaked in oil so that 20 it is substantially waterproof and non absorbent. The inserts are pressed in and are frictionally held in the recesses 11. The inserts are preferably square so that a large bearing surface is provided, whereby the bearing pressure is reduced 25 and consequently wear is likewise reduced. Since the inserts are square, they may be inserted in the recesses so that after one side is worn, the inserts may be removed and reinserted so that another side is presented outwardly to serve as a bearing surface. If desired, the arms 2 may be 30 made of round stock and the edges of the recesses may be peened over as at 13, see Fig. IV, to assist in maintaining the inserts in the recesses 11.

As shown in Fig. II, the inserts 10 may be made 35 in sections 14, 15 and 16 as it will be readily understood that the middle portion 15 receives the greatest wear because of the movement of the tool or work holder 1. These sections 14, 15, and 16 may be interchanged from time to time, thereby 40 obtaining the maximum of wear from a given amount of bearing material. For example, when section 15 becomes worn, it may be removed and exchanged with section 14. When section 14 is worn, it may be exchanged with section 16. 45 Each of these sections may be removed and reinserted to present a different surface as described above.

It is to be understood that the edges of the recesses of the arms shown in Figs. I and III may 50 be peened over to assist in holding the inserts 10. Also the inserts used in this modification may be divided into sections as shown in Fig. II.

Although specially treated leather has been found to be very satisfactory, any other suitable 55 material, such as fiber or rubber, may be substituted for the leather. The inserts 10 may also be made of any suitable composition, such as felt impregnated with powdered graphite or other self-lubricating material. The inserts 10 may also be 60 made of suitable metal having free graphite to act as a self-lubricant. Any other suitable bearing metal may be used for the inserts 10.

The recesses 11 may also be formed wider at the bottom than at the top and the inserts may 65 be complementary to the recesses so that they may be slipped in from the ends.

It may also be mentioned that the bearing inserts 10 may be placed in the uprights 3 as well

as, or instead of, in the arms 2 without departing from the spirit and scope of the invention.

From the foregoing description it will be apparent that I have provided a novel and improved attachment for abrading apparatus which greatly reduces the cost of replacement of wearing parts, maintains the accuracy and eliminates noise in 5 operation.

Having described my invention, I claim:

1. An abrading apparatus having means for 10 supporting a tool and means for guiding the work to be abraded over said tool, said means having normally related members engaging each other for holding the work in axial relation with the tool during the guiding of the work over said tool, one of said members having a groove extending longitudinally thereof on the side adapted to be engaged by the other member causing a portion of its cross section to assume a U shape and a replaceable bearing member of a semi-resilient material of a dimension slightly larger in 15 cross section than the cross sectional area of the groove forced into said groove substantially throughout the length thereof and frictionally held in said groove along its longitudinal edges 20 by the elastic after working of said material.

2. An abrading apparatus having means for 25 supporting a tool and means for guiding the work to be abraded over said tool, said means having normally related members engaging each other 30 for holding the work in axial relation with the tool during the guiding of the work over said tool, one of said members having a groove extending longitudinally thereof on the side adapted to be engaged by the other member causing 35 a portion of its cross section to assume a U shape, one of the longitudinal edges of said grooved portion being deflected in a direction inwardly of the groove and a replaceable bearing member of a semi-resilient material forced inwardly of said 40 groove and held therein by said deflected longitudinal edge and by friction created by the elastic after working of said material.

3. An abrading apparatus having means for 45 supporting a tool and means for guiding the work to be abraded over said tool, said means having normally related members engaging each other for holding the work in axial relation with the tool during the guiding of the work over said tool, one of said members having a groove extending 50 longitudinally thereof on the side adapted to be engaged by the other member causing a portion of its cross section to assume a U shape and a replaceable bearing member of a semi-resilient material of a dimension slightly larger 55 in cross section than the cross sectional area of the groove forced into said groove substantially throughout the length thereof and frictionally held in said groove along its longitudinal edges by the elastic after working of said material, said 60 replaceable bearing member being divided into a plurality of sections whereby the section which receives the least wear during the abrading operation may be interchanged with the section which normally receives the greatest wear, where- 65 by a maximum amount of wear can be obtained from a given amount of bearing material.

JOHN A. KEENAN.
